UNITED STATES PATENT OFFICE

149,518

DESIGN FOR A COOKING KIT

Carl Rendler, Los Angeles, Calif.

Application August 27, 1946, Serial No. 132,904

Term of patent 14 years

(Cl. D44—1)

To all whom it may concern:

Be it known that I, Carl Rendler, a citizen of the United States, residing at Los Angeles, in the county of Los Angeles and State of California, have invented a new, original, and ornamental Design for a Cooking Kit, of which the following is a specification, reference being had to the accompanying drawing, forming part thereof.

Fig. 1 is a perspective view of a cooking kit showing my new design in the closed condition.

Fig. 2 is a perspective view thereof in the open position. In the latter view one of the pans of the kit is shown with the bottom side up, while its companion pan is shown with the bottom side down and with the handle therefor resting within the pan.

Fig. 3 is a perspective view of the bottom cover pan of the kit.

Fig. 4 is a perspective view, per se, of one of the twin pans of the kit with the lifting handle therefor in the applied condition.

I claim:

The ornamental design for a cooking kit, substantially as shown and described.

CARL RENDLER.
